SPRING KNOTTING MACHINE

Fred R. Zimmerman, Chicago, Ill., assignor to
 Nachman Springfilled Corporation, Chicago,
 Ill., a corporation of Illinois

Application September 17, 1937, Serial No. 164,330

14 Claims. (Cl. 140—101)

The invention has for its main object to provide a simple and efficient machine for knotting upholstery springs of different sizes and composed of wire of gauges commensurate with the size and load carrying capacity of the spring.

5 Upholstery springs of various types such as hour-glass, cone and cylindrical, are delivered from conventional machines known as "coilers" with their terminal end portions spaced from the nearest points disposed substantially radially of the extremities of said springs. To coil said end portions about the substantially radially opposed portions of said springs has heretofore been accomplished by first bending said terminal end portions inwardly so that a predetermined part of each of said end portions became disposed in overlapped relation to the portion of the body of the spring to provide a projection of predetermined length extending inwardly of the part overlapped thereby, said length being determined by the number of turns or coils desired to embrace the overlapped portion of the spring. These operations preceded the final knotting operation performed generally by a pedal operated machine, both operations at each end of the spring being relatively slow and, therefore, costly.

One of the objects of the present invention is to provide a knotting machine which performs each bending operation immediately preceding the knotting operation, so that both said operations are performed substantially simultaneously.

A suitable embodiment of the invention is illustrated in the accompanying drawings, where:

35 Fig. 1 is a front elevation partly in section of a machine constructed in accordance with the invention.

Fig. 2 is a vertical sectional view of the machine taken on the line 2—2 of Fig. 1.

40 Fig. 3 is a side elevation of the machine, also partly in section.

Fig. 4 is a view similar to Fig. 3 showing the operating parts of the machine in another position.

45 Fig. 5 is a fragmentary sectional view on an enlarged scale, taken on the line 5—5 of Fig. 4.

Fig. 6 is a fragmentary top plan view of the machine.

Fig. 7 is a fragmentary perspective view of an 50 upholstery spring adapted to be knotted by the machine, showing a terminal end portion bent to overlap another portion thereof preparatory to effecting knotting of the spring.

Fig. 8 is a view similar to Fig. 7 showing the 55 completion of the knotting operation.

Fig. 9 is a perspective view of the coiling or knotting head of the machine.

Fig. 10 is a detail perspective view on an enlarged scale showing the spring carrying element of the machine.

The machine comprises a suitable frame equipped with bearings for actuating shaft 1 thereof, which carries a loose pulley 2.

Rigidly mounted upon the shaft 1 is a clutch member 3 constituting an element of a conventional punch-press clutch which will not be described because well known to those skilled in the art. The engagement of the member 3 with the pulley 2 is manually controlled by means of a manually operable lever 55 (Fig. 2) which controls the actuation of said shaft 1 at the will of the operator and is actuated by a rod 56.

Rigid with the shaft 1 is a spur gear wheel 4 which, as shown in Fig. 2, is a segmental gear of a well-known type which meshes, during a part 20 of its revolution, with the spur gear wheel 5 on a countershaft 6. Said spur gear wheel 5 meshes with a spur gear wheel 7 on a second countershaft 8 and the latter, in turn, meshes with the spur gear teeth of the coiling head 9, said spur 25 gear teeth 10 of the head 9 being shown in detail in Fig. 9 and being shown also in dotted lines in Fig. 4. The gear ratio between said spur gear wheel 4 and the said coiling head 9 is such that at each complete revolution of said wheel 30 4, the head 9 is rotated through a predetermined number of complete revolutions. Obviously, the gear ratio may be changed and varied by replacing the respective gear wheels 4, 5 and 7 with other gear wheels for increasing or reducing the 35 number of complete revolutions through which the head 9 is rotated at each actuation of the wheel 4.

The coiling head 9 is equipped with a longitudinal slot 11 extending throughout its length and 40 which is radially disposed, the innermost or end wall of said slot being semi-cylindrical and concentric with the axis of rotation of said head 9. Said head is equipped at one end with what may be termed a cam member 12, also shown in Fig. 45 9, which is provided with a normally horizontally disposed top face 13 aligned with the diametric plane of the head 9 which is coincident with the said slot 11 thereof. Said face 13 terminates at the innermost end of the slot 11 at one end and 50 at the circumferential face of the said head diametrically opposite the mouth of the slot 11.

The said cam member 12 has an arcuate face which is flush with the cylindrical face of the head 9, the cut-away portion 14 of said cam 55

member being adapted to engage the inwardly projecting terminal portion 15 of the spring 16, shown in Fig. 7, to effect coiling thereof about the adjacent convolution 17 of said spring, as shown in Fig. 8.

Pivotedly mounted upon a stud shaft 18 of the machine frame is a rocking member 19 which is substantially of inverted L-shape and terminates at the outer end of its upper arm in a plate 19a. 10 Mounted upon a stud shaft 20 disposed between the ends of the member 19 is an anti-friction roller 21 which is maintained normally engaged with a cam 22 rigid with the shaft 1 by means of a tension spring 23.

15 The cam 22 is equipped with a recess 24 and with circumferential or cylindrical face, the bottom wall of said recess being concentric with the axis of rotation of said cam and the end walls of said recess being flaring and substantially 20 ogee-curved, so that the roller 21 may ride easily out of the recess upon the circumferential face of the cam, and vice-versa, as the latter is rotated. Mounted upon the upper and outermost end portion of the member 19 is a spring carrier plate 25, shown in detail in Fig. 10, which is disposed normally in forward position and to one side of the head 9 when the latter is at rest, as shown in Fig. 3. Said plate 25 is equipped with a raised portion 26 having parallel edges, one of which is 25 flush with one side edge of said plate 25 and has its other edge parallel with and spaced from the other side edge of said plate 25. The end portion of the part 26 of the plate 25 has an arcuate front edge spaced from the front edge of the 30 plate 25 and an arcuate shoulder 28 spaced from the arcuate edge 26a. The plate 25 is equipped at its forward left hand corner, as shown in Fig. 10, with a projection 29 having an arcuate face which is opposed to the left hand forward corner 35 of the arcuate edge 27.

As shown in Fig. 6 the terminal end portion of a terminal coil 30 of a spring 16 is disposed in contact with the arcuate surface 27 of said part 26 of the plate 25, and is engaged also by the projection 29, whereas, the next adjacent convolution 17 of the spring is engaged, in part, by the arcuate shoulder 28.

Mounted upon the frame of the machine is an adjustable stop 31 against which the extremity of 50 the terminal coil of the spring 16 is caused to abut in order to position the spring as desired in the machine preparatory to effecting knotting thereof. An adjustable stop 32 disposed upon the portion 19a of member 19 behind the plate 25, 55 engages a portion of the terminal coil of the spring 16 which is substantially diametrically opposed to the portion of said spring which is engaged with the arcuate shoulder 28.

Pivotedly mounted between its ends upon a 60 stud shaft 33 carried by the member 19 at a point substantially vertically aligned with the stud shaft 20, is a spring-clamping lever 34, one end of which is engaged with the tension spring 35 for maintaining said lever normally in the position 65 shown in Fig. 3.

The machine frame is equipped with an upwardly projecting head 36 which is equipped with the bearing for the opposite end portions of the head 9, the said respective end portions of the latter disposed at opposite sides of the spur gear teeth 18 being cylindrical and housed in said bearings. The latter are equipped with slots which 70 normally are aligned with the slot 11 of said head 9.

75 Mounted in said head 36 is an adjustable shaft

37 which carries an eccentric 38 disposed in the path of the substantially ogee-curved formation 39 of one end portion of the head 40 of the lever 34, said head 40 being provided with a recess 41 which is adapted to receive the portion of the 5 convolution 17 of the spring 16, shown in Fig. 6, immediately adjacent one end of the said head 9, said end portion or head 40 of said lever 34 being disposed angularly to the body of said lever as shown in Fig. 6.

The said shaft 37 is equipped at its other end with a nut 42 by means of which it is clamped against rotation after effecting adjustment of the position of said eccentric 38 relatively to the head 9 to cause said lever 34 to firmly engage a portion 17 of the spring 16 engaged with the shoulder 28 to clamp said spring against movement during the coiling operation, said eccentric being shown in position wherein the head 40 of the lever 34 is adapted to engage a spring 16 composed of wire of heaviest gauge which the machine is capable of operating upon. Obviously, the said eccentric 38 will be moved from the position shown in Fig. 3 to another position, depending upon the gauge of wire of the spring 25 which is being operated upon.

Obviously, the plate 25 is interchangeable with other similar plates wherein the arcuate shoulder 28 is of less height in each instance than the portion 17 of the spring adapted to be engaged therewith, so that the said head 40 of the clamping lever 34 may engage said portion of the spring disposed in engagement with said shoulder to clamp the same firmly against the surface between the shoulders 28 and 27.

It will be obvious that as soon as the rotation of the cam 22 begins, the anti-friction roller 21 will ride over the adjacent end wall of the recess 24 and upon the circumferential face of said cam. This will cause the said member 19 to swing to the position shown in Fig. 4 whereby the portion of the terminal coil of the spring opposed to the mouth of the slot 11 of the head 9 will be moved into said slot and practically in contact with the innermost wall of the latter. At the same instant that this occurs, the said head 40 of the clamping lever 34 will be moved by contact with the eccentric 38 into the position shown in Fig. 4 wherein it clamps against movement the portion of the convolution 17 of the spring next adjacent to that about which the terminal end portion 15 of the latter is to be coiled during the succeeding coiling operation, which may be said to begin almost instantly after the beginning of rotation of said cam 22.

When the parts above described are disposed in the position shown in Fig. 4, the terminal coil of the spring 16 will have its end portion 15 disposed in the position shown in Fig. 5 and the convolution 17 of said spring will overlie said 60 terminal portion 15 between the ends of the latter and will be maintained firmly in said position by means of said head 40 of the clamping lever 34.

During movement of the said plate 25 carried by the said member 19, the terminal end portion 15 of the spring 16 will be engaged in the recess 43 in the left hand end wall 43 of the head 9 between the slot 11 and the cut-away portion 14 of the cam member 12 of said head and will be bent from the position indicated in dotted lines at 44 in Fig. 7 to the full line position of Fig. 5.

The punch-press clutch will cause the shaft 1 to rotate only through a single complete revolution, whereupon it is automatically disengaged. To prevent the same from rotating more than 75

one revolution by reason of momentum imparted to said shaft 1 and parts carried thereby, said shaft is equipped with a brake disk 45 and a brake shoe 46 which is held in firm engagement with said brake disk 45 by means of the tension spring 47 shown in Figs. 3 and 1.

It will be noted by reference to Fig. 2 that the rotation of the head 9 will not begin until the gear wheel 4 shall have completed a quarter of a revolution and before its teeth engage the teeth of the gear wheel 5, so that prior to the rotation of the head 9, the spring will be bent as shown in Fig. 5 and the parts positioned relatively to the head 9 and the cam member 12 thereof, illustrated in Fig. 5, wherein it is clearly indicated that the end wall of the head 9 which meets with the cutaway portion 14 of the cam, is supplied with the recess 48, also shown in Fig. 9, and into which the terminal end portion 15 of the spring projects until it is forced out of said recess by rotation of said head 9.

The gear wheel 5 is rigid with a hub 49 which is provided with a V-shaped recess 50 in which the V-shaped projection 51 of an arm 52 engages as shown in Fig. 2, said arm being pivotally secured at its lower end to a stud-shaft 53 and held in engagement with the said hub 50 by means of tension spring 54.

Obviously, following release of the teeth of the gear wheel 5 from the teeth of the gear wheel 4, the rotation of said wheel 5 will be stopped by means of the said lever 52, so that substantially the final quarter revolution of the shaft 1 will be effected without actuating the gear wheel 5.

It is believed that the operation of the machine will be fully and readily understood from the foregoing description, but is briefly reviewed as follows:

The member 19 and other operating parts of the machine are normally disposed in the position shown in Fig. 2.

The operator then places one end of the upholstery spring upon the plate 25 in the position shown in Fig. 6 with the extremity of a terminal coil of said spring in contact with the stop 31 and with a portion of said spring engaged with the stop 32. A portion of a convolution 17 of the spring is engaged with the arcuate shoulder 28.

The operator then actuates the punch press clutch control lever to cause the shaft 1 to rotate through a complete revolution and thereby causes the cam 22 to throw the member 19, which carries the plate 25, to the position shown in Fig. 4.

During this slightly upward swing of said member 19, the extremity of the spring 16 is disengaged from the stop 31 and said spring 16 is swung so that the portion of the coil 17 immediately beyond the right hand end of the arcuate shoulder 27 is moved into the slot 11 of the coiling head 9. During this movement the terminal end portion 15 of the spring 16 is bent, as most clearly shown in Fig. 5, and at the same time the head 40 of the clamping lever 34 engages the portion of the convolution 17 of the spring adjacent the point at which it is overlapped by said end portion 15. This projecting of the terminal coil into the slot 11 of the head 9 occurs before the head 9 begins to rotate, it being obvious from Fig. 2 that the rotation of the head 9 will begin only when the teeth of the gear wheel 4 are thrown into mesh with the teeth of the gear wheel 5.

Rotation of the head 9 causes the cutaway portion 14 of the cam member 12, integral with the said head, to coil the terminal end portion 15 of

the spring about the convolution 17 thereof to complete the knotting operation at one end of the spring.

As soon as the shaft 1 has completed its revolution, the anti-friction roller 21 will have been returned to the position in the recess 24 of the cam 22 shown in Fig. 3 and simultaneously therewith the head 40 of the clamping member 34 will have been restored to the position shown in Fig. 3.

The spring is then removed and its position reversed or another spring inserted in place thereof, whereupon the aforesaid operation is repeated.

Interchangeable heads 9 are provided for operations on springs composed of different gauges of wire.

The portion of the head 9 midway between its ends is directly opposed to the longitudinal axis of the spring to be operated upon and the position of the plate 25 used with each head 9 employed is so spaced from the left hand end of the head 9 as to cause the terminal end 15 of the spring to be bent as shown in Fig. 5 when said plate is moved to the position therein shown.

I claim as my invention:

1. A machine of the kind specified comprising a longitudinally slotted rotatable coiling head, a manually controlled power actuated mechanism for imparting to said head a predetermined number of complete revolutions at each actuation thereof, a spring carrier equipped with means for firmly holding a spring in predetermined position thereon, and in opposed relation to said slot of said head, means included in said mechanism for moving said carrier toward said head for positioning a predetermined portion of the spring carried thereby in said slot prior to the beginning of the actuation of said head, a spring clamping member mounted on said carrier, and means on the machine frame disposed in the path of said clamping member for throwing the same into engagement with the spring at the instant of completion of said movement of said carrier and so maintaining the same during the period of rotation of said head, and means arranged for cooperation with said carrier for effecting bending of a predetermined length of a terminal portion of the spring during said movement of said carrier to cause said end portion to overlap said first-named portion and hold the same in engaging relation to said head for effecting coiling of a part of said end portion about said first-named portion of said spring, said last-named means cooperating also with said clamping means.

2. A machine of the kind specified comprising a longitudinally slotted rotatable coiling head, a manually controlled power actuated mechanism for imparting to said head a predetermined number of complete revolutions at each actuation thereof, a spring carrier equipped with means for firmly holding a spring in predetermined position thereon, and in opposed relation to said slot of said head, means included in said mechanism for moving said carrier toward said head for positioning a predetermined portion of the spring carried thereby in said slot prior to the beginning of the actuation of said head, a spring clamping member mounted on said carrier, and means on the machine frame disposed in the path of said clamping member for throwing the same into engagement with the spring at a point contiguous to the said head at the instant of completion of said movement of said

carrier and so maintaining the same during the period of rotation of said head, and means arranged for cooperation with said carrier for effecting bending of a predetermined length of a terminal portion of the spring during said movement of said carrier to cause said end portion to overlap said first-named portion and hold the same in engaging relation to said head for effecting coiling of a part of said end portion about 10 10 said first-named portion of said spring, said last-named means cooperating also with said clamping member.

3. A machine of the kind specified comprising a longitudinally slotted rotatable coiling head, a manually controlled power-actuated mechanism for imparting to said head a predetermined number of complete revolutions at each actuation thereof, a spring carrier equipped with means for firmly holding a spring in predetermined position thereof, and in opposed relation to said slot of said head, means included in said mechanism for moving said carrier toward said head for positioning a predetermined portion of the spring carried thereby in said slot prior to 20 20 the beginning of the actuation of said head, a spring clamping member mounted on said carrier, and means on the machine frame disposed in the path of said clamping member for throwing the same into engagement with the spring at a point contiguous to that of overlap of the first-named portion of said spring by said terminal end portion thereof at the instant of completion of said movement of said carrier and so maintaining the same during the period of rotation 30 30 of said head, and means arranged for cooperation with said carrier for effecting bending of a predetermined length of a terminal portion of the spring during said movement of said carrier to cause said end portion to overlap said first-named portion and hold the same in engaging relation to said head for effecting coiling of a part of said end portion about said first-named portion of said spring, said last-named means cooperating also with said clamping member.

4. A machine of the kind specified comprising a longitudinally slotted rotatable coiling head, a manually controlled power-actuated mechanism for imparting to said head a predetermined number of complete revolutions at each actuation thereof, a spring carrier equipped with means for firmly holding a spring in predetermined position thereof, and in opposed relation to said slot of said head, means included in said mechanism for moving said carrier toward said head for positioning a predetermined portion of the spring carried thereby in said slot prior to the beginning of the actuation of said head, a spring clamping member mounted on said carrier, and means on the machine frame disposed in the path of said clamping member for throwing the same into engagement with the spring at a point contiguous to that of overlap of the first-named portion of said spring by said terminal end portion thereof and at a point contiguous to the portion of the head engaging said overlapping end portion during rotation of said head at the instant of completion of said movement of said carrier and so maintaining the same during the period of rotation of said head, and means arranged for cooperation with said carrier for effecting bending of a predetermined length of a terminal portion of the spring during said movement of said carrier to cause said end portion to overlap said first-named portion and hold the same in engaging relation to said head

for effecting coiling of a part of said end portion about said first-named portion of said spring, said last-named means cooperating also with said clamping member.

5. A machine of the kind specified comprising a coiling head equipped with radial slot to receive a portion of a spring about which said head is adapted to rotate, power actuated, manually controlled mechanism for rotating said head through a predetermined number of revolutions at each actuation thereof, a cam member rigidly mounted upon one end of said head, a spring carrier opposed to the slot of said head when the latter is at rest, means associated with said carrier for enabling the spring to be mounted upon the latter in a given position, a rotatable cam included in said mechanism and operatively engaged with said carrier for moving the same to a position wherein a predetermined portion of the spring is disposed in said slot prior to beginning and so maintaining the same until completion of rotation of said head, said carrier cooperating with said head to bend a terminal end portion of the spring into overlapping relation to another portion thereof during said movement of said carrier, and a clamping means associated with said carrier for engagement with the last-named portion of said spring at substantially the instant of completion of said movement of said carrier.

6. A machine of the kind specified comprising a coiling head equipped with radial slot to receive a portion of a spring about which said head is adapted to rotate, power actuated, manually controlled mechanism for rotating said head through a predetermined number of revolutions at each actuation thereof, a cam member rigidly mounted upon one end of said head, a self-restoring spring carrier opposed to the slot of said head when the latter is at rest, means associated with said carrier for enabling the spring to be mounted upon the latter in a given position, a rotatable cam included in said mechanism and operatively engaged with said carrier for moving the same to a position wherein a predetermined portion of the spring is disposed in said slot prior to beginning and so maintaining the same until completion of rotation of said head, said carrier cooperating with said head to bend a terminal end portion of the spring into overlapping relation to another portion thereof during said movement of said carrier and disposing the same in the path of said cam member on said head for causing the latter to coil the same about the portion of the spring immediately adjacent one end of the part thereof disposed within said slot during rotation of said head, and a clamping means associated with said carrier for engagement with the last-named portion of said spring at substantially the instant of completion of said movement of said carrier.

7. A machine of the kind specified comprising a coiling head equipped with radial slot to receive a portion of a spring about which said head is adapted to rotate, power actuated, manually controlled mechanism for rotating said head through a predetermined number of revolutions at each actuation thereof, a cam member rigidly mounted upon one end of said head, a self-restoring spring carrier opposed to the slot of said head when the latter is at rest, means associated with said carrier for enabling the spring to be mounted upon the latter in a given position, a rotatable cam included in said mechanism and operatively engaged with said carrier for moving the same to a position

tion wherein a predetermined portion of the spring is disposed in said slot prior to beginning and so maintaining the same until completion of rotation of said head, said carrier cooperating with said head to bend a terminal end portion of the spring into overlapping relation to another portion thereof during said movement of said carrier and disposing the same in the path of said cam member on said head for causing the latter to coil the same about the portion of the spring immediately adjacent one end of the part thereof disposed within said slot during rotation of said head, a spring clamping lever mounted on said carrier, and a member rigid with the machine frame and disposed in the path of said lever for throwing the latter into position to engage the last-named portion of the spring upon the carrier against movement during rotation of said head.

20 8. A machine of the kind specified comprising a coiling head equipped with radial slot to receive a portion of a spring about which said head is adapted to rotate, power actuated, manually controlled mechanism for rotating said head through a predetermined number of revolutions at each actuation thereof, a cam member rigidly mounted upon one end of said head, a self-restoring spring carrier opposed to the slot of said head when the latter is at rest, means associated with said carrier for enabling the spring to be mounted upon the latter in a given position, a rotatable cam included in said mechanism and operatively engaged with said carrier for moving the same to a position wherein a predetermined portion of the spring is disposed in said slot prior to beginning and so maintaining the same until completion of rotation of said head, said carrier cooperating with said head to bend a terminal end portion of the spring into overlapping relation to another portion thereof during said movement of said carrier and disposing the same in the path of said cam member on said head for causing the latter to coil the same about the portion of the spring immediately adjacent one end of the part thereof disposed within said slot during rotation of said head, a spring clamping lever mounted on said carrier, and a member rigid with the machine frame and disposed in the path of said lever for throwing the latter into position to engage the last-named portion of the spring upon the carrier against movement during rotation of said head.

9. In a machine of the kind specified, a rotatable coiling head adapted to receive and rotate about a portion of a spring and equipped with means for engaging a terminal end portion of said spring disposed in overlapped relation, another portion thereof for coiling said terminal portion about the last-named portion, a carrier for the spring equipped with shoulders opposed to said head for engaging said respective portions of said spring, an end of one of said shoulders being opposed substantially to said means on said head and from which a terminal end portion of said spring is adapted to project, a stop arranged for cooperation with said end of said last-named shoulder for determining the length of terminal end portion of the spring adapted to be coiled about the coil thereof engaged with the other of said shoulders, power actuated mechanism for causing said carrier to be moved to project the first-named portion of the spring into said head, the latter cooperating with said carrier to effect bending of the said terminal end

portion of said spring into overlapping relation to the second-named coil of said spring preceding the beginning of rotation of said head, said mechanism including means for effecting rotation of said head throughout a predetermined number of complete revolutions during which said first-named means on said head engage and coil said terminal portion of said spring about the portion of the latter overlapped thereby.

10. A machine of the kind specified comprising a carrier for a spring equipped with a pair of shoulders disposed at different elevations and spaced from each other, the lower of said shoulders adapted to engage a portion of a terminal coil of the spring spaced from an extremity thereof and the higher shoulder adapted to engage a portion of the next adjacent coil of the spring, a longitudinally slotted rotatable coiling head opposed to and adapted to receive and rotate about a predetermined portion of the spring disposed beyond said shoulder of said carrier, means on said head cooperating with one end of the lower shoulder for bending the portion of the spring disposed between the said extremity thereof and the portion engaged with said lower shoulder as said carrier is moved to project said predetermined portion of said spring into said head, means on one end of said head adapted to engage the bent terminal end thereof as said head is rotated for coiling the latter about a portion of said predetermined portion of the spring about which said head is rotatable, and power actuated means for moving said carrier in the direction for projecting and bending the respective portions of the spring for engagement by said head and thereafter effecting rotation of said head, thereby to effect knotting of the spring.

11. A spring knotting machine comprising a rotatable coiling head equipped with a radial slot adapted to receive a portion of a spring about which said head is adapted to rotate, a spring carrier disposed at one side of said head and spaced forwardly of the slot of the latter, a pair of shoulders on said carrier adapted to engage a portion of a terminal coil of said spring and a portion of the next adjacent coil opposed thereto, another portion of said last-named coil opposed to said head being adapted to be projected into the slot of said head, means at one end of said head adapted to cooperate with one end of the shoulder of the carrier engaged with the first-named portion of the spring to effect bending of the adjacent terminal end portion of spring into underlapping relation to the second-named portion of said spring as said carrier is moved to project the latter into the slot of said head, a shoulder at said end of said head equipped with said first-named means for engaging said bent terminal end of the spring as said head rotates for coiling the same about the second-named coil of the spring, and power actuated mechanism for moving said carrier to the position wherein the said bending operation is completed and said second-named portion of said spring is disposed in said slot and thereafter effecting rotation of said head to complete the knotting operation.

12. A spring knotting machine comprising a rotatable coiling head equipped with a radial slot adapted to receive a portion of a spring about which said head is adapted to rotate, a spring carrier disposed at one side of said head and spaced forwardly of the slot of the latter, a pair of shoulders on said carrier adapted to engage a portion of a terminal coil of said spring

and a portion of the next adjacent coil opposed thereto, another portion of said last-named coil opposed to said head being adapted to be projected into the slot of said head, means at one 5 end of said head adapted to cooperate with one end of the shoulder of the carrier engaged with the first-named portion of the spring to effect bending of the adjacent terminal end portion of spring into underlapping relation to the sec- 10 ond-named portion of said spring as said carrier is moved to project the latter into the slot of said head, a stop disposed for engagement with the extremity of said terminal portion of the spring for determining the length thereof, a 15 shoulder at said end of said head equipped with said first-named means for engaging said bent terminal end of the spring as said head rotates for coiling the same about the second-named coil of the spring, and power actuated 20 mechanism for moving said carrier to the position wherein the said bending operation is completed and said second-named portion of said spring is disposed in said slot and thereafter effecting rotation of said head to complete the 25 knotting operation.

13. A spring knotting machine comprising a rotatable coiling head equipped with a radial slot adapted to receive a portion of a spring about which said head is adapted to rotate, a 30 spring carrier disposed at one side of said head and spaced forwardly of the slot of the latter, a pair of shoulders on said carrier adapted to engage a portion of a terminal coil of said spring and a portion of the next adjacent coil opposed thereto, another portion of said last-named coil 35 opposed to said head being adapted to be projected into the slot of said head, means at one end of said head adapted to cooperate with one end of the shoulder of the carrier engaged with the first-named portion of the spring to effect 40 bending of the adjacent terminal end portion of spring into underlapping relation to the second-named portion of said spring as said carrier is moved to project the latter into the slot of said head, a shoulder at said end of said head equipped with said first-named means for engaging said bent terminal end of the spring as said head rotates for coiling the same about the sec- 45

ond-named coil of the spring, automatic spring clamping means on said carrier for maintaining the second-named portion of said spring engaged with said carrier during rotation of said head, and power actuated mechanism for moving said 5 carrier to the position wherein the said bending operation is completed and said second-named portion of said spring is disposed in said slot and thereafter effecting rotation of said head to complete the knotting operation. 10

14. A spring knotting machine comprising a rotatable coiling head equipped with a radial slot adapted to receive a portion of a spring about which said head is adapted to rotate, a spring carrier disposed at one side of said head 15 and spaced forwardly of the slot of the latter, a pair of shoulders on said carrier adapted to engage a portion of a terminal coil of said spring and a portion of the next adjacent coil opposed thereto, another portion of said last-named coil 20 opposed to said head being adapted to be projected into the slot of said head, means at one end of said head adapted to cooperate with one end of the shoulder of the carrier engaged with the first-named portion of the spring to effect 25 bending of the adjacent terminal end portion of said spring into underlapping relation to the second-named portion of said spring as said carrier is moved to project the latter into the slot of said head, a stop disposed for engagement with the extremity of said terminal portion of the spring for predetermining the length thereof, a shoulder at said end of said head equipped with said first-named means for engaging said bent terminal end of the spring as said head 30 rotates for coiling the same about the second-named coil of the spring, automatic spring clamping means on said carrier for maintaining the second-named portion of said spring engaged with said carrier during rotation of said 35 head, and power-actuated mechanism for moving said carrier to the position wherein the said bending operation is completed and said second-named portion of said spring is disposed in said slot and thereafter effecting rotation of 40 said head to complete the knotting operation. 45
